(57) **CLAIM**

The ornamental design for a dual blade nail clipper, as shown and described.

DESCRIPTION

FIG. 1 is a perspective view of our new design showing a dual blade nail clipper in an open position;
 FIG. 2 is a front view of the dual blade nail clipper of FIG. 1;
 FIG. 3 is a rear view of the dual blade nail clipper of FIG. 1;
 FIG. 4 is a left side view of the dual blade nail clipper of FIG. 1;
 FIG. 5 is a right side view of the dual blade nail clipper of FIG. 1;
 FIG. 6 is a top view of the dual blade nail clipper of FIG. 1;
 FIG. 7 is a bottom view of the dual blade nail clipper of FIG. 1;
 FIG. 8 is a front view of the dual blade nail clipper of FIG. 1 in a closed position; and,
 FIG. 9 is a right side view of the dual blade nail clipper of FIG. 1 in a storage position.

1 Claim, 9 Drawing Sheets
